(57) **CLAIM**

The ornamental design for an insect deflector for vehicle, as shown and described.

DESCRIPTION

FIG. 1 is a view in perspective of the insect deflector for vehicle of the present invention shown mounted on the engine compartment cowl of a vehicle;

FIG. 2 is an enlarged front elevation view of the insect deflector for vehicle of the present invention;

FIG. 3 is an enlarged top plan view of the insect deflector for vehicle of the present invention;

FIG. 4 is an enlarged right side elevation view of the insect deflector for vehicle of the present invention;

FIG. 5 is an enlarged left side elevation view of the insect deflector for vehicle of the present invention;

FIG. 6 is an enlarged rear elevation view of the insect deflector for vehicle of the present invention; and,

FIG. 7 is an enlarged bottom view from beneath the insect deflector for vehicle of the present invention.

The broken line showing of environment is for illustrative purposes only and forms no part of the claimed design.
